(57) **CLAIM**

The ornamental design for a dispensing container for thread sealant as shown and described.

DESCRIPTION

1. Dispensing container for thread sealant

1.1 : is a perspective view;

1.2 : is a front view;

1.3 : is a rear view;

1.4 : is a right side view;

1.5 : is a left side view;

1.6 : is a top view; and,

1.7 : is a bottom view.

The dot-dash lines in the drawings depict the bounds of the claimed design and form no part thereof. The dashed lines depict portions of the dispensing container for thread sealant that form nor part thereof.

(Continued)

Dispensing container for thread sealant used for the dispensing of a sealing filament contained in the dispensing container for thread sealant.

1 Claim, 7 Drawing Sheets
